UNITED STATES PATENT OFFICE.

ZACHARY T. HEAL, OF NEW YORK, N. Y.

DESIGN FOR A WINDOW-SHADE RUNNER.

SPECIFICATION forming part of Design No. 32,623, dated May 1, 1900.

Application filed April 3, 1900. Serial No. 11,383. Term of patent 3½ years.

To all whom it may concern:

Be it known that I, ZACHARY T. HEAL, of the city of New York, borough of Brooklyn, in the county of Kings and State of New York, have invented and produced a new and original Design for a Window-Shade Runner, of which the following is a full, clear, and exact description.

Reference is to be had to the accompanying drawings, forming a part of this specification, in which similar characters of reference indicate corresponding parts in both the figures.

Figure 1 is a perspective view of a window-shade runner, showing my design; and Fig. 15 2 is an edge view thereof.

The leading feature of the design for a window-shade runner consists of a body-bar 1, on one side of which is a hook-shaped projection 2, and extended from the body-bar in an

opposite direction to that of the part 2 are 20 arms 3, which terminate in claws 4, the said claws being arranged at an obtuse angle with relation to the body-bar. A curved projection is shown on one edge of the body-bar, and inward of this projection a perforation 25 is shown through the body-bar.

Having thus described my invention, I claim as new and desire to secure by Letters Patent--

The design for a window-shade runner, as 30 herein shown and described.

In testimony whereof I have signed my name to this specification in the presence of two subscribing witnesses.

ZACHARY T. HEAL.
